BOBBIN CLUTCH

Howard A. Simmons, Milford, Mass., assignor of
one-half to James Read Kimball, Hopedale,
Mass.

Application October 5, 1949, Serial No. 119,671

4 Claims. (Cl. 242—46.4)

1

This invention relates to bobbin clutches, and more particularly to the construction and arrangement of a rotatable mechanism providing a resilient head for the reception of the hollow end of a bobbin or the like.

Mechanisms of this general construction are commonly employed in the textile industry for supporting and driving a bobbin while yarn or a similar strand is being wound thereon. Such mechanisms usually include an upright spindle over which the bobbin is placed, with the lower end of the bobbin engaging a resilient head carried by the spindle. These prior mechanisms are subject to serious disadvantages. In some cases the spindle becomes badly worn after a comparatively short period of service. Often the mechanism is expensive to manufacture, and difficult and costly to repair. Some prior mechanisms fail to engage the bobbin with sufficient expansive force to ensure proper driving thereof.

It is accordingly one object of the invention to provide a bobbin clutch which will drive a bobbin in the desired manner without causing any wear on the supporting spindle.

It is a further object of the invention to provide a comparatively simple, inexpensive and efficient bobbin clutch such that all parts subject to wear can be readily replaced at low cost.

With these and other objects in view, as will be apparent to those skilled in the art, the invention resides in the combination of parts set forth in the specification and covered by the claims appended hereto.

Referring to the drawing illustrating one embodiment of the invention, and in which like reference numerals indicate like parts,

Fig. 1 is a vertical section through a bobbin clutch with a bobbin mounted thereon, the section being taken on the line 1—1 of Fig. 4;

Fig. 2 is a view similar to a portion of Fig. 1, with the bobbin removed;

Fig. 3 is an elevation of the mechanism shown in Fig. 2;

Fig. 4 is a section taken on the line 4—4 of Fig. 1;

Fig. 5 is a top plan view of a clutch body forming a part of the mechanism;

Fig. 6 is a section taken on the line 6—6 of Fig. 5;

Fig. 7 is a top plan view of a ring forming a part of the mechanism;

Fig. 8 is a section taken on the line 8—8 of Fig. 7; and

Fig. 9 is an elevation of a spring forming a part of the mechanism.

2

The embodiment illustrated comprises an upright spindle 10 having an upwardly tapered upper portion 11 forming a blade. The lower portion of the spindle is arranged to be supported in suitable bearings (not shown) in a well-known manner so that the spindle may be rotated at high speed. On the lower portion of the tapered blade 11 there is mounted a whirl or pulley 12 having a tapered bore 14 which engages the blade 11 tightly to drive the same. The bore 14 is long enough to provide a firm and dependable driving fit with the blade. The upper end of the whirl 12 is provided with a recess in the form of an annular groove 15 coaxial with the blade.

A clutch body 16 is mounted on the blade 11 directly above the whirl 12. This body 16 is formed generally as an upright cylinder with a diameter substantially equal to that of the recess 15. A tapered bore 18 extends axially through the body 16, and a counterbore 19 is provided in the lower end of the body. The bore 18 is so proportioned that it will engage the tapered blade 11 tightly, with the lower end of the body 16 extending part way into the annular recess 15 in the upper end of the whirl 12, as shown in Figs. 1 and 2. The upper portion 20 of the body is somewhat reduced in diameter as compared with the remaining portion, for a short distance down from the top of the body, as best shown in Figs. 5 and 6. Four circumferentially spaced generally radial holes 22 are provided in the portion 20, these holes being located immediately above the larger diameter portion of the body. The holes 22 preferably, but not necessarily, extend through to the tapered bore 18. Four vertical grooves 23 are provided in the outer surface of the body 16 throughout the larger diameter portion thereof, these grooves being aligned with the respective holes 22. Thus the upper end of each groove 23 is positioned directly beneath and close to the outer end of one of the holes 22. The depth of each groove 23 is preferably approximately equal to the difference between the radii of the lower and upper portions of the body 16. Thus the lower surfaces of the grooves are substantially aligned with the outer surface of the upper portion 20.

Each of the grooves 23 is arranged to receive a spring in the form of a vertically elongated resilient member 25. This spring may be of any desired cross section, for example circular cross section, and it may be made of steel piano wire. As shown in Fig. 9, a short portion 26 at the upper end of the spring is bent inwardly to a substantially horizontal position whereas the major por-

tion of the spring is bowed outwardly. When the parts are assembled, as shown in Fig. 2, the portion 26 of each spring is located within one of the radial openings 22 in the body 16, while the lower end of the spring extends into the groove 15 in the top of the whirl 12.

In order to hold the upper ends of the springs 25 in place, there is provided a device in the form of a cylindrical sleeve or ring 28 having a bore 29 of the proper size to fit the upper portion 20 of the body 16 with a light press fit. The outside diameter of the sleeve is substantially equal to that of the main part of the body 16. The lower end of the sleeve is beveled downwardly and outwardly at 30 (Fig. 8), or otherwise cut away, so that it will enclose the upper ends of the springs 25 at assembly (Fig. 2) and hold the portions 26 in the openings 22. To facilitate removal of the sleeve 28, so that the springs may be replaced when worn, two diametrically opposed radial holes 31 are provided in the sleeve for the reception of a suitable tool.

The clutch mechanism as described is adapted to support and drive a bobbin 33 of any suitable and well-known construction. The bobbin illustrated is formed principally of wood, and it includes a cylindrical metal sleeve 34 which is firmly secured within the lower portion of the wooden body. The internal diameter of this sleeve 34 is such that it will fit closely over the clutch body 16, the lower end of the bobbin engaging the top of the whirl 12. As the bobbin is pushed downwardly over the clutch body, the sleeve 34 will force the bowed springs 25 inwardly into the grooves 23, as shown in Figs. 1 and 4, and the springs will provide an outward pressure on the inner surface of the sleeve to retain and drive the bobbin. As the bobbin is placed over the clutch body and the springs are straightened, their lower ends will move somewhat further downwardly into the groove 15 in the whirl.

It will be noted that the portions 26 of the springs 25 do not touch the spindle blade 11, and the spindle is not subjected to wear in service. The springs are very inexpensive, and they can be easily replaced if they become worn by contact with the bobbin. The construction is relatively simple to manufacture and thoroughly dependable in operation.

Having thus described my invention, what I claim as new and desire to secure by Letters Patent is:

1. A bobbin clutch comprising an upright spindle, a whirl mounted on the spindle and having an opening in its upper end, a clutch body mounted on the spindle above the whirl and having a longitudinally extending groove in its outer surface, the body having an opening in its upper portion which extends inwardly in a generally radial direction, the said body opening being aligned with the groove and spaced downwardly from the upper end of the body, and a vertically elongated and outwardly bowed spring located in the groove and having an upper portion which extends inwardly into the body opening to prevent appreciable vertical movement of the upper

end of the spring, the lower end of the spring extending into the said whirl opening while free to move downwardly therein as the spring is straightened by the placing of a bobbin on the clutch body, the clutch body engaging both the upper and the lower portions of the spring to resist the inward pressure of the bobbin against the spring.

2. A bobbin clutch as set forth in claim 1, in which a device is mounted on the upper portion of the clutch body above the body opening, the said device having a portion which engages the outer surface of the spring adjacent the upper end thereof to hold the spring substantially in contact with the clutch body and thus prevent any appreciable radial movement of the spring within the said body opening.

3. A bobbin clutch comprising an upright spindle, a whirl mounted on the spindle and having a recess in its upper end providing an internal cylindrical surface coaxial with the spindle, a generally cylindrical clutch body mounted on the spindle above the whirl and having a plurality of circumferentially spaced generally radial openings in its upper portion and somewhat below its upper end, the clutch body having longitudinal grooves extending downwardly from the respective openings, an outwardly bowed spring located in each groove and having its upper end bent inwardly and lying within the corresponding opening so that the upper portion of the spring is prevented from appreciable vertical movement, and an annular device mounted on the upper portion of the clutch body above the said openings and engaging the outer surfaces of the springs adjacent their upper ends to hold the springs substantially in contact with the clutch body and thus prevent any appreciable radial movement of the springs within the said openings, the lower ends of the springs extending into the said whirl recess while free to move downwardly therein as the springs are straightened by the placing of a bobbin on the clutch body, the clutch body engaging both the upper and the lower portions of the springs to resist the inward pressure of the bobbin against the springs.

4. A bobbin clutch as set forth in claim 3, in which the clutch body is provided with a portion of reduced diameter above the generally radial openings, and in which the annular device is in the form of a sleeve fitting closely over the said portion of reduced diameter, the lower end of the sleeve being beveled in a downward and outward direction and engaging the outer surfaces of the springs adjacent their upper ends.
